UNITED STATES PATENT OFFICE.

ERNEST J. TURNER, OF PITTSBURGH, PENNSYLVANIA.

HOT TOP.

Application filed January 26, 1926. Serial No. 83,841.

The present invention relates broadly to ingot making, and more particularly to an improved form of hot top adapted for bodily addition to an ingot mold in known 5 manner to improve the character of the ingot which is produced in the mold.

It is known at the present time to make hot tops in whole or in part of refractory material, or of slag, cinders, cement or the 10 like. It is also known to make hot tops of a wide variety of shapes, the shape usually being governed by the contour of the mold with which the hot top is to be used.

My invention relates to an improvement 15 in hot tops irrespective of their contour or composition, and may be embodied in any of the above or other types of hot tops. One of the objects of this invention is to decrease the weight of the hot top whereby the handling thereof is facilitated, and to improve 20 its heat insulating properties. These improved results are conveniently obtained by forming the hot top of generally cellular nature with a plurality of suitably arranged, 25 and preferably closed air spaces connected by relatively narrow webs.

In the accompanying drawings there is 30 shown more or less diagrammatically for purposes of illustration only one form of hot top embodying the present invention, it being understood that the drawings do not define the limits of my invention as changes 35 in the construction, contour, arrangement and location of supporting means and the like may be made at will without departing from the spirit of the invention or the scope of my broader claims.

In the drawings:

Figure 1 is a top plan view of a hot top 40 embodying the present invention; and

Figure 2 is a side elevation of the construction illustrated in Figure 1.

In carrying out the present invention any 45 desired composition may be determined upon and thereafter formed into suitable shape by molding, extrusion or the like, as customary for example, in the manufacture of hollow tiles to thereby provide a body portion 2 of any desired contour with suitable 50 supporting means 3 such as ribs, lugs or the like. The walls of the body portion are preferably compound, comprising an inner shell 4 and an outer shell 5 connected by relatively narrow ribs or webs 6 providing a minimum area of solid wall space

throughout the main body of the tile consistent with the desired strength. Intermediate these ribs or webs are cells or air spaces 7. The hot top, after being partially formed as herein recited, may be completed 60 in any desired manner as by mudding over the ends of the cells or air spaces to thereby provide closed air pockets minimizing heat transfer and radiation from the interior of the hot top outwardly.

It will be understood by those skilled in the art that not only does a construction of the character herein indicated function to maintain the metal adjacent the upper end of the ingot in molten condition for a longer 70 period than has been possible with hot tops as heretofore constructed where provision for actual combustion or slow burning has not been provided, but that it materially decreases the weight of the hot tops, thereby 75 facilitating handling.

In practice it has been found that due to the better insulating properties of a hot top of cellular construction, the tendency to 80 spall or crack is reduced to a minimum.

The present hot top lends itself to coating or impregnation in known manner with suitable waterproofing compounds where desired, and also to coating with any desired material, fusible or otherwise, adapted to 85 facilitate subsequent relative movement between the shrinkage ingot and the hot top.

The advantages of the present invention arise from the provision of a generally cellular hot top of any desired contour and 90 composition which may, if desired, be left in its natural state or coated or impregnated in known manner with any desired materials as now contemplated in the art.

I claim:

1. As an article of manufacture, a hot top 95 formed of refractory material having a plurality of air spaces formed in the walls thereof.

2. As an article of manufacture, a hot top 100 formed of refractory material having compound walls connected by webs providing air spaces therebetween.

3. As an article of manufacture, a hot top 105 for ingot molds formed of refractory material having at least a portion of its walls formed with a closed-in air pocket.

In testimony whereof I have hereunto set my hand.

ERNEST J. TURNER.
